(57) **CLAIM**

The ornamental design for a container closure, as shown and described.

DESCRIPTION

FIG. 1 is a top view of a first embodiment of a container closure.

FIG. 2 is a perspective view thereof.

FIG. 3 is a side elevation view thereof.

FIG. 4 is a top view of a second embodiment of a container closure.

FIG. 5 is a perspective view thereof; and,

FIG. 6 is a side elevation view thereof.

The underside of the container closure is not shown and is not part of the claimed design.

All sides of the container closure are identical.

The broken line and the space contained inside of the broken line depict portions of the container closure that form no part of the claimed design.

1 Claim, 4 Drawing Sheets
